APPARATUS FOR OBTAINING FIBERS FROM
THE STALKS OF FLAX AND OTHER BAST
PLANTSAlbert Ernest Dodd, Woodford, Dromara,
Northern IrelandApplication May 23, 1938, Serial No. 209,582
In Great Britain September 27, 1937

1 Claim. (Cl. 19—24)

This invention relates to apparatus for decorticating the stalks of flax and other bast plants for the purpose of removing woody or pulpy matter and obtaining fibers therefrom, the invention having particular reference to apparatus for this purpose of the kind embodying a series of pairs of fluted rollers through which the flax or the like is passed, the rollers of each pair being pressed into contact with one another by spring 5 or other suitable means.

The object of the present invention is to devise an improved form of machine of the above character which will enable a larger output of better quality fiber to be obtained from a machine of 10 given capacity as compared with apparatus of this kind as hitherto proposed or adopted.

The invention consists in apparatus of the kind referred to in which the coarseness of the flutes varies progressively through the machine 15 so that the coarsest flutes are at the feed end and the finest flutes at the exit end, each succeeding pair of rollers throughout the machine revolving at a slightly higher surface speed than the preceding pair and the spring or like pressure 20 urging the rollers into contact but not bottoming contact varying with the flute pitches so that the pressure is greatest for the coarsest pitches and lowest for the finest pitches.

Further features of the invention will be ap- 25 parent from the description given hereafter.

The accompanying drawing illustrates one mode of carrying out the invention.

Figure 1 is a side elevation (with parts omitted) 30 of one form of apparatus in accordance with the invention, and

Figure 2 is a plan.

In carrying my invention into effect in one convenient manner I form my improved apparatus with any suitable foundation, framework 35 or bed-plate *a*, and upon this I arrange a series of pairs of rollers *b* *c* which are fluted or similarly formed upon their surface, and which are so arranged that when pressed into contact the flutes of one roller are prevented from bottoming 40 the grooves of the companion roller by approximately $\frac{1}{16}$ of an inch, for the coarsest pitched rollers and a proportionally lesser amount for the finer pitches. One roller of each pair, say the lower roller *c*, is mounted in fixed bearings 45 and is arranged to be power driven by suitable gearing *d* while the companion roller *b* of each pair is mounted in sliding bearings and spring pressed into contact with the lower roller, the spring pressed roller being either positively driven 50 or driven by frictional contact with the fixed

bearing roller as may be desired. The rollers of succeeding pairs are varied in diameter so as to vary the peripheral speeds and they also vary in the pitch of the flutes, and the spring pressure is so adjusted that it is greatest for the 5 largest rollers and those having the coarsest pitch of flutes, and is lowest for the smallest rollers and those having the finest pitch. For example, I have found very satisfactory results by the use of spring pressures varying from 250 10 lbs. for rollers having a number of flutes equal to four times the diameter, in inches, to 100 lbs. for rollers having a number of flutes equal to twelve times the diameter of the roller, in inches.

In the specific embodiment of the invention 15 illustrated in the drawing I provide the machine with 34 pairs of intermeshing fluted rollers, and arranged in four sections *A*, *B*, *C* and *D*. The first section *A*, for example, would contain three pairs of rollers varying in diameters from $4\frac{5}{16}$ " to 5" 20 and having 18 flutes, and 3 pairs with the same varying diameters and 28 flutes. The second section *B* consists of seven pairs of rollers varying progressively in diameter from $4\frac{5}{16}$ " outside diameter to $4\frac{1}{2}$ " and having 8 flutes per 25 inch diametral pitch. The third section *C* would consist of 9 pairs of rollers varying progressively in diameter from 3.5" diameter to 3.7" and each roller would have 10 flutes per inch diametral pitch. The fourth section *D* would have 12 pairs 30 of rollers varying progressively in diameter from $2\frac{23}{32}$ " to $2\frac{37}{48}$ " and each roller would have 12 flutes per inch diametral pitch. In the first section the depth of space between a flute of one roller and the corresponding groove of the companion roller would be .065" for the first three pairs and .0514" for the second three pairs. The corresponding dimensions for the second, third and fourth sections would be .050", .046" and .0227" respectively. The spring pressures employed would vary from 250 lbs. for the rollers with 4 flutes per inch diametral pitch, to 100 lbs. for the rollers with 12 flutes per inch diametral pitch. Each of the four sections would be driven 40 from one main driving shaft by separate gearing so arranged that the percentage increase of surface speed between the last roller pair of one section and the first roller pair of the succeeding section is the same as between the succeeding roller pairs in each section. For this purpose a suitable "change" wheel would be incorporated 45 in the driving gears for each several section.

I have found that with a machine constructed in accordance with the foregoing description I am able to reduce the bulk of the flax by 70 per 50 55

cent. which is a very considerable advance on results hitherto obtained with machines of similar capacity.

It will be understood, however, that the foregoing dimensions are given purely by way of example, and not limitation, as I may vary the number of pairs of rollers in the machines, the diameters and pitch distances of flutes, and the surface speeds of the rollers, depending upon any practical requirements that may have to be fulfilled.

I claim:

Apparatus for decorticating the stalks of flax and other bast plants of the kind embodying a

series of pairs of fluted rollers through which the flax or the like is passed, means for pressing the rollers of each pair into contact with one another, the pitch of the flutes of each pair of rollers progressively decreasing through the machine, the pressure of the pressing means varying with the flute pitches of each pair of rollers so that the pressure is greatest for the coarsest pitches and lowest for the finest pitches, and means for revolving each succeeding pair of rollers throughout the machine at a slightly higher surface speed than the preceding pair.

ALBERT ERNEST DODD.
